(57) **CLAIM**

The ornamental design for a “bendable dash pedestal,” as shown.

DESCRIPTION

FIG. 1 is a generally perspective view of a “bendable dash pedestal” showing my new design;

FIG. 2 is a front view thereof;

FIG. 3 is a rear view thereof;

FIG. 4 is a side view thereof, the opposite side being the mirror image thereof;

FIG. 5 is a top plan view thereof;

FIG. 6 is a bottom plan view thereof; and,

FIG. 7 is a generally perspective, illustrative view showing the mounting device connected to a supporting surface.

The broken line showing of a supporting surface is included for the purpose of illustrating environment and forms no part of the claimed design.
